UNITED STATES PATENT OFFICE.

OSWALD T. FLEURY, OF BOSTON, MASSACHUSETTS.

SAFETY-RAZOR.

1,273,842.

Specification of Letters Patent. Patented July 30, 1918.

Application filed December 18, 1917. Serial No. 207,702.

To all whom it may concern:

Be it known that I, OSWALD T. FLEURY, a citizen of the United States, residing at Boston, in the county of Suffolk, State of Massachusetts, have invented certain new and useful Improvements in Safety-Razors; and I do hereby declare the following to be a full, clear, and exact description of the invention, such as will enable others skilled 10 in the art to which it appertains to make and use the same.

This invention is an improvement in razors and has particular reference to a safety razor.

15 The practice of removing hairs from the axilla is, at the present time, becoming more predominant and, in order to accomplish this purpose, the ordinary safety razor is sometimes employed but has been found 20 more or less unsatisfactory owing to the fact that access cannot readily be obtained to the curvature of the arm pit to remove the hairs therefrom with the straight edge blades commonly used. Chemical preparations 25 are also marketed for removing these hairs and it is well known that such means often times prove injurious to the user.

It is therefore an object of the present invention to provide a razor which will readily and efficiently remove the hairs from the axilla and, to this end, use is preferably made of a blade provided with a curved cutting edge and having its body of an arcuate formation.

35 Another object is the provision of a detachable holder of improved construction for the blade which will securely maintain a guard in operative relation thereto.

A further object is to provide a razor of 40 this character which is simple in construction, easy to manufacture and wherein the parts may be readily and quickly assembled and detached should it be desired to replace the blade.

45 The inventive idea involved is capable of receiving a variety of mechanical expressions one of which, for the purpose of illustrating the invention is shown in the accompanying drawing, wherein:—

50 Figure 1 is a front elevation of the razor constructed in accordance with the invention.

Fig. 2 is a side elevation.

Fig. 3 is an end view.

55 Fig. 4 is a section on the line 4-4 of Fig. 1.

Fig. 5 is a section on the line 5-5 of Fig. 2.

Fig. 6 is a detail perspective view of one of the members of the holder.

The invention is illustrated in what is now believed to be its preferred form and comprises a blade 10 made of a piece of metal bent longitudinally into arcuate formation and having a straight longitudinal edge 11 and an opposite cutting edge 12 which is curved about an axis that intersects a plane of the blade and which extends longitudinally of the handle presently to be described. With a blade of this construction, it will be apparent that, by reason of its curvature, the same will effectively engage the curvature of the arm pit and remove the hairs therefrom. A guard 13 is associated with the blade 10 and curved similar thereto and provided upon the edge adjacent the cutting edge 12 with a plurality of bent fingers 14. The blade 10 and guard 13 are each provided with transverse registering openings 15 and 16, respectively, disposed adjacent the ends of said members for a purpose to presently appear.

The invention further comprises a holder preferably consisting of a pair of complementary clamping members 17 which include sides 18 that diverge toward the blade and guide. The end of each side 18 adjacent the blade and guard is bent to provide an extension 19 which engages over the outer face of the blade 10 and which is reduced to provide the locking tongue 20 adapted to be extended through the adjacent registering openings 15 and 16 so that the tongue will be disposed adjacent the inner face of the guard 13. The opposite end of each of the clamping members 17 is formed to provide the substantially semicircular and solid handle portion 21 which co-operates with the opposite portion to provide a handle. In order that the parts may be retained in co-operative relation, the outer ends of the handle portions 21 are preferably screw threaded to receive an internally threaded cap 23 which will effectively prevent spreading of the clamping members 17 when the razor is being used.

In practice, when it is desired to assemble the razor, the locking tongues 20 are first passed through the registering openings 15 and 16 after which the handle portions are adjusted toward each other until their flat surfaces are engaged. In so adjusting the clamping members it will be apparent that

the same will swing about the inner ends of the locking tongues as pivots and that therefor said tongues will be adjusted toward the inner face of the guard 18 and 5 exert a pressure thereagainst which will result in the guard and blade being clamped in binding engagement between the extensions 19 and tongues 20. The cap 28 may then be threaded into engagement with the 10 outer ends of the portions 21 whereupon the razor will be ready for use.

What is claimed is:--

1. A razor including a blade, a guard associated with said blade, a holder for the 15 blade and guard including separable clamping members each of which is provided at one end with an extension engaging said blade and a tongue projecting from the extension and through said blade and guard 20 and engaging the latter, and means for retaining said clamping members in operative position.
2. A razor including a blade, a guard associated with said blade, a holder for the 25 blade and guard including separable clamping members each of which is provided at one end with an extension engaging over the end of said blade and a tongue projecting from the extension and passing downwardly 30 and through said blade and guard and engaging the latter, the other end of each clamping member being formed to provide a handle portion which coöperates with the similar portion of the other clamping member, and means for detachably securing said 35 handle portions in coöperating relation.
3. A razor including a blade, a guard as-

sociated with said blade, a holder for the blade and guard including complementary clamping members each of which is provided at one end with an extension engaging said 40 blade and a tongue projecting from the extension and through said blade and guard and engaging the latter, the other end of each clamping member being formed to provide a handle portion which coöperates with the similar portion of the other clamping member, and a cap threaded upon said 45 handle portions for retaining the same in coöperating relation.

4. A razor including a blade bent longitudinally and having a cutting edge curved about an axis intersecting a plane of the blade, a guard associated with said blade, a holder for the blade and guard including 50 separable clamping members detachably connected to the blade and guard and each of which is provided at one end with an extension engaging said blade and a tongue projecting from the extension and through 55 said blade and guard and engaging the latter, the other ends of said clamping members being adjustable away from each other whereby to detach the clamping members from the blade and guard, and means for 60 retaining said clamping members in operative position.

In testimony whereof, I affix my signature in the presence of two witnesses.

OSWALD T. FLEURY.
